UNITED STATES PATENT OFFICE.

ELLIS W. TEST, OF MICHIGAN CITY, INDIANA.

CAR-ROOF AND RUNNING-BOARD SUPPORT.

1,324,217.

Specification of Letters Patent.

Patented Dec. 9, 1919.

Application filed February 21, 1919. Serial No. 278,443.

To all whom it may concern:

Be it known that I, ELLIS W. TEST, a citizen of the United States, and resident of Michigan City, county of Laporte, and State 5 of Indiana, have invented certain new and useful Improvements in Car-Roof and Running-Board Supports, of which the following is a specification and which are illustrated in the accompanying drawings, forming 10 ing a part thereof.

The invention relates to a car roof and running board structure and has for an object the securing of the roofing sheets to the car without the use of nails. A further object is the provision of a securing means of the nature referred to in which the joint between the roofing sheets is made weather-tight and yet sufficiently flexible to allow for weaving action of the car in use. A further 15 object of the invention is the provision of means for holding the running board saddle to the car roof without the use of holding means which project through the car roof. A further object of the invention is the provision 20 of car roof holding means which protect the heads of the bolts which secure its anchor to the car body plate.

In the accompanying drawings,

Figure 1 is a plan view of one end of the 30 car roof,

Fig. 2 is a side view of a portion of the car roof, partially in longitudinal section,

Fig. 3 is a transverse section on line 3—3 35 of Fig. 1,

Fig. 4 is a side view of the car roof showing the end of one of the holding plates,

Fig. 5 is a transverse section on line 5—5 40 of Fig. 4,

Fig. 6 is a section corresponding to Fig. 5, but showing a modification, and

Fig. 7 is a section on an enlarged scale, showing the roofing joint and holding plate.

The car roof frame comprises the usual carline 1, ridge pole 2, plate 3, fascia 4, roof 45 boards 6. 5 designates the siding of the car. Purlins, not shown, may be used if desired.

The car roof covering sheets, indicated at 7, consist of sheets preferably of metal, having at each margin one or more corrugations, three corrugations being shown in the drawings. When in place upon the car roof these corrugated margins are overlapped, the corrugations mating together. The 55 sheets preferably extend from one edge to

the other of the roof and are downturned over the fascia.

Holding plates 8 are corrugated to conform to the configuration of the margin of the overlying roofing sheet at each joint and are superimposed thereon. These holding plates are substantially continuous from one edge of the roof to the other, and means are shown for placing the holding plates under tension whereby they are caused to bear 65 down upon the overlapped edges of the roofing sheets. If the holding plate is continuous from one edge of the roof to the other the means of securing the end of the holding plate, shown in Fig. 6, as a bracket 9, 70 secured to the fascia by bolt 10, and a second bracket 11, secured to the holding plate by rivet 12, will result in the tightening of the holding plate when the bolt 13 connecting said brackets has its nut screwed down, 75 the tightening of which will put strain upon the holding plate.

Preferably, however, I use the anchoring plate shown at 14 (Fig. 5) which anchoring plate is secured to the fascia by bolts 10' passing through the anchoring plate, the fascia, and the car body plate. Anchor plate 14 has a hook 15 formed thereon near its bottom edge and holding plate 8 has an eye 16' suitable for engagement over said hook. The eye 85 16' is formed in the downturned end 16 of the holding plate and it will be observed that the arrangement of the parts, as shown in Figs. 4 and 5, will result in the effectual covering of the heads of the bolts 10' thereby 90 protecting them from the weather, preventing their loss should their nuts become loosened and furthermore, preventing water from flowing in through the hole through which the bolt is passed. In this modification the holding plates are placed under tension by means of a bolt 17 passing through the upstanding portions of brackets 18, 18, riveted to the ridge end of the holding plates by rivets, as 19. When the bolt is 100 tightened and eyes 16' of the two holding plates, corresponding to the joint in question, are engaged over the hook 15, the overlapped margins of the roofing sheets will be firmly pressed down upon the roofing boards. 105

A novel form of running board saddle is indicated generally at 20. This saddle comprises a top wall 21, side walls 22, and a bottom wall 23. The bottom wall of the saddle is shaped to fit the contour of the car roof 110

whereby the side walls become wider at the end of the saddle than at the center thereof. The ends of the hollow saddle structure are left open. The bottom wall of the saddle is 5 corrugated to correspond to the configuration of the holding plate and in use is superimposed directly on this holding plate. To allow brackets 18 to project into the interior of the saddle, the saddle is cut away 10 at the central portion of its bottom wall, as indicated at 24. A bolt 25 is passed transversely through the walls of the saddle and under bolt 17 whereby the bolt 17, firmly held to the roof by brackets 18 and holding 15 plates 8, will prevent the saddle from lifting. Running board members 26 are bolted or riveted to the upper wall of the running board saddle. The peculiar arrangement of the running board saddle and the brackets 20 18 result in protecting these brackets and their connections with the holding plates from the weather.

If desired the corrugations in the holding plates may be made slightly deeper than 25 those in the margins of the roofing sheets and as a result thereof the edges of the holding plates and also the bottom of the corrugations of the same will cause pressure to be placed upon the roofing sheets at those 30 points nearest to the roofing boards. This will result in tighter edges where the elements seek to find entrance, and a better joint between the roofing sheets. Moreover, the edge of the holding plate adjacent the 35 edge of the roofing sheet which is on top may be extended beyond the same and bent downward to contact with the underlying roofing sheet thereby protecting the point of greatest vulnerability of the joint.

40 The corrugations at one edge of each sheet may be made slightly more shallow and less abrupt of curvature than those at the other margin of the same sheet which arrangement will result in increased flexibility of 45 joint. This will result in a relation of parts as indicated in Fig. 7, wherein the more shallow and less abruptly curved corrugations of one sheet are shown as overlapped by the deeper and more pointed corrugations 50 of the next sheet, producing spaces as 27 between the crests of the corrugations allowing relative movement between the respective sheets while maintaining the integrity of the joints and of the body of the 55 sheets.

The same result may be attained by providing alternate sheets with identical corrugations on their two margins but differing from the corrugations upon the remainder in which case alternate sheets will have both their margins underlying and alternate sheets will have both their margins overlying contiguous sheets.

I claim as my invention:

65 1. A car roof covering comprising roofing

plates provided with overlapping corrugated margins, a corrugated holding plate covering and mating with said corrugated margins and means acting on said plate in an endwise direction to tension the same. 70

2. A car roof covering comprising sheets extending transversely of the car roof with their margins overlapping, a holding plate of a width corresponding with said overlap, means to anchor said plate at each edge 75 of the roof and means endwise applied for tensioning said plate.

3. A car roof covering comprising roofing sheets having overlapping mating corrugated margins, a corrugated holding plate 80 mating with and covering said margins upon each side of the car roof, anchoring means for said plates at the edges of the roof and means for drawing the proximate ends of said plates toward each other at the 85 ridge.

4. A car roof structure comprising car body plates and fascia, roofing sheets extending transversely of the roof and having their margins overlapped, a holding plate 90 covering said overlapped margins extending from edge to edge of the roof and bent down at its ends over the fascia, an anchor plate, bolts extending through said anchor plate, fascia and car body plates, securing 95 means on said anchor plate for said holding plate, said holding plate when in engagement with said securing means covering said bolt ends.

5. In combination a hollow running board 100 saddle comprising top, side and bottom walls, said bottom wall being shaped to fit the transverse contour of the car roof and being cut away in the region corresponding to the ridge of the car, means for securing 105 the car roof in place comprising a part spaced from the roof and projecting through the cut away portion of the saddle and a member coacting with said means and saddle to secure the saddle in place. 110

6. In combination, a car roof comprising roof plates, means for binding the plates to the roof, a running board saddle, the means for binding the plates to the roof interlocking with the saddle block to secure it to the 115 roof.

7. The combination with a car roof of a running board saddle block superimposed thereon, and means wholly external of the roof for securing the roof in place and the 120 saddle block thereto.

8. A car roof and running board saddle structure comprising means to secure the roof covering in place including a bolt 125 spaced above the car roof, a running board saddle, a member on said saddle extending below said bolt whereby said saddle is held in place.

9. A car roof and running board saddle structure comprising roofing sheets having 130

overlapped corrugated margins, corrugated holding plates covering said margins, anchoring means for said holding plates at the fascia, brackets secured to the ridge end of 5 said holding plates, a bolt connecting said brackets and spaced above the ridge, a hollow saddle having its bottom wall shaped to fit said roof and the corrugations of said holding plates and seated thereon, the portion 10 of the bottom of said saddle at the ridge being cut away whereby said brackets project into the interior of said saddle and a bolt extending transversely of said saddle and under said first named bolt.

15 10. The combination of a car roof having surface elevations and depressions with a running board saddle block shaped to fit said surface elevations and depressions as well as the transverse contour of the roof 20 and means wholly external of the roof for securing the roof in place and the saddle block to the roof.

11. A joint for a car roof covering comprising overlapping corrugations, a holding 25 plate superimposed upon said corrugations having corrugations corresponding to but deeper than said overlapping corrugations

and means to cause said holding plate to press down upon said overlapping corrugations whereby the pressure of said holding 30 plate is exerted at its edges and at the bottom of its corrugations.

12. A car roof comprising roofing sheets having alternate longitudinal elevations and depressions at their margins, the margins of 35 the sheets being adapted to be lapped together, the margins adapted to overlap differing in configuration from those adapted to underlap whereby flexibility of joint will be secured.

13. A car roof comprising roofing sheets each having corrugations at its side margins, the corrugations at one margin of each sheet differing in curvature from those at the other whereby, when margins of contiguous 45 similar sheets are placed in overlapping relation, flexibility of joint will be secured.

14. A flexible joint comprising overlapped corrugated margins of roofing sheets, the corrugations of the upper margin being 50 deeper and more abrupt in curvature than those of the under margin.

ELLIS W. TEST.
